OVEN LINER

Alfons Barnsteiner, Mansfield, Ohio, assignor to
Westinghouse Electric Corporation, East Pittsburgh, Pa., a corporation of Pennsylvania

Application October 18, 1949, Serial No. 122,105

5 Claims. (Cl. 126—19)

1

This invention relates to an oven liner fabricated of sheet metal, and has for an object to provide an oven liner that has greater resistance to distortion stresses, which may be incurred during its manufacture and in baking and other cooking processes.

It is a further object of this invention to provide a sheet metal oven liner having a more rigid front end member, thus assuring an improved and more uniform door seal under all cooking temperature conditions.

It is another object of this invention to provide an improved oven liner that can be manufactured at no increase in cost.

In order to insure good baking results in an oven, uniform heat distribution throughout the oven interior must be maintained. Although various factors must be taken into account in manufacturing an oven having uniform baking qualities, one of the most important and heretofore troublesome factors has been the provision of an oven in which the door seal remains uniform under all baking conditions. Due to uneven expansion and warpage of the liner upon heating, air leakage through the door-to-liner seal would vary with varying oven temperatures, upsetting and impairing proper heat distribution within the oven.

In accordance with my invention, I form the oven liner with corner portions adjacent the open front end of the liner, which corner portions are of a form to serve as corner braces to resist warpage or distortion. These corner portions are disposed relatively close to the intersection of the adjacent walls at the front end and then are spaced progressively further from such intersection in rearward direction. Preferably, the corner portion is of minimum radius at the front end and of progressively greater radius in rearward direction. The front end portion of the liner thus provided is of larger cross-sectional dimensions at its forward end than at its rearward end, facilitating its removal from the dies. No unnecessary bulges are present that would necessitate the use of special dies or other tools. Such corner portions can be formed in the drawing of the front end portion of the oven liner, and are thereby provided without any additional operation and without any increase in cost.

In the drawings,

Fig. 1 is a top plan of a drawn sheet metal pan member which provides the front end member and the rear wall member of an oven liner;

Fig. 2 is an elevational view of the pan member;

2

Fig. 3 is a fragmentary section taken on line III—III of Fig. 1; and

Fig. 4 is a section taken on line IV—IV of Fig. 3;

Fig. 5 is a longitudinal section of the completed oven liner; and,

Fig. 6 is a fragmentary perspective view, showing a corner brace portion.

Referring to the drawings in detail and especially Fig. 5, a fabricated sheet metal oven liner designated 10 is shown comprising a tubular wrap-around body member 12 having a top wall 14, a bottom wall 16 and two side walls 18 (only one shown). A rear wall member 20 of pan-like shape and having a peripheral offset marginal portion 22 is attached in lapping relation with the rear marginal portion of the body member 12. A preferable manner of attaching the members 12 and 20 is by spot-welding (denoted by X's) at a plurality of points.

20 A front end member 24 of generally tubular shape and having a peripheral offset marginal portion 26 is attached in lapping relation with the front marginal portion of the body member 12 by spot-welding (denoted by X's). The front end member has a top wall 28, a bottom wall 30 and side walls 32 (only one shown) defining a generally rectangular access opening for the oven liner. The front marginal portions of the member 24 are bent outwardly to form an L-shaped peripheral flange 34 adapted to be abutted by an oven door (not shown) and to act as a seal for closing the oven liner when in use. It is to be understood that for the oven to have good baking properties it is essential that the seal at the flange be unaffected by temperature changes.

As best shown in Figs. 1 and 2, a preliminary pan-like structure 38, of generally rectangular shape and having a bottom surface portion 40 and four side walls 42, is drawn from sheet metal by 40 a set of suitable dies (not shown). This structure is adapted to be severed on a line X—X¹ to provide the front member 24 and the rear member 20 in their initial stage of fabrication. After severing, these members are formed, respectively, with the offset portions 26 and 22, which latter are then welded to the body member 12.

The preliminary pan-like structure 38, before severing, will first be described. The junctions between adjacent side walls are curved to provide smooth curved surfaces 44 and to eliminate corners which are difficult to clean. Also, the junctions between the bottom 40 and the side walls 42 may be curved for the same reasons. A preliminary peripheral flange 46 of substantially rec-

tangular shape, is disposed adjacent the walls 42, and is provided by the unformed sheet metal during the drawing process.

As well understood in the art, the structure 38 may be drawn to shape in one single drawing operation. If desired, at various spaced portions, the walls 42 may be formed with a plurality of integral gusset-like indentations 48 which extend into the flange 46 to stiffen the flange in a conventional manner. At each corner adjacent the flange 46 there is formed a curved portion 50 joining the adjacent walls 42 and the curved surface 44. Since the four curved portions 50 thus provided may be identical, only one such portion will be described in detail, it being understood that the other portions will be similarly formed. As best shown in Fig. 4, the curved portion 50 is disposed within the angle formed by the intersection Y of the planes of the adjacent walls 42. Its rear end conforms to the curvature of the rounded surface 44, which has a relatively large radius R^1 . The front portion is disposed more closely to the intersection Y of the planes of the walls 42. It is more sharply curved than the portion 44 and may desirably be formed on the arc of a circle having a shorter radius R^2 . Intermediate its front and rear ends, the curvature of the portion 50 changes gradually and smoothly from the short radius of curvature at the front to the larger radius of curvature at the rear. Thus, the portion 50 is outwardly inclined with respect to the rounded surface 44 by an angle B and has a substantial area when projected in a plane parallel to the wall 40, as shown in Fig. 4, thereby possessing a substantial corner bracing effect. It will be noted that the curved portion 50 is substantially tangential to the adjacent walls 42.

The shape of the portion 50 may be formed in any desirable manner and need not follow any exact mathematical form. For example, it may be formed, in whole or in part, as a frusto-conical surface having the center F-F' and having radii R^3 and R^4 at the front and rear ends of the corner portion. Such form has the advantage that the concave surface of the matrix or intaglio die (not shown) may be formed by a rotating cutting tool, instead of by laborious and less exact methods. Obviously, the junctions between the frusto-conical surface thus formed and the walls 42 may be blended together to provide a smooth contour to the finished oven liner. As well understood, the matrix die may be dressed at these junctions to impart the smooth contour.

A strong bracing effect is thus imparted to the adjacent walls and flange to form a rigid structure which is highly resistant to bending or warpage. It will be noted that the curved surfaces 50 are inclined outwardly with respect to the curved surfaces 44, thus permitting the pan structure to be easily formed in a die and to be removed therefrom. The added bracing effect is thus attained without any increase in manufacturing cost, since no added manufacturing operations are necessary to produce the corner braces. It will also be seen that the corners have also been strengthened without disturbing the appearance of the flange or the walls. Subsequent warpage of the liner upon heating will be minimized due to the increased rigidity and an improved door seal thus attained. The curved portion 50, although inclined outwardly, lies entirely within the space formed by the planes intersecting at Y as previously noted,

hence the walls 32 still maintain their plane appearance and the rectangular aspect of the opening is preserved.

As fully explained and claimed in Barnsteiner et al. patent application, Serial No. 116,901, filed September 21, 1949, after the oven liner 10 has been assembled and spot-welded into one rigid unit, as previously described herein, the preliminary flange 46 is reformed to the L-shaped flange 34.

Although I have shown and described only one embodiment of the curved portion 50, other shapes which may be attained in drawing and forming dies may be found advantageous, the chief requisite, as explained above, being that the portion 50 be inclined outwardly relative to the rounded surface 44, with its front portion disposed more closely to the intersection Y than its rear portion.

What I claim is:

1. A fabricated sheet metal oven liner for a range comprising a front end member having a tubular portion, said tubular portion having top, bottom and side walls defining a substantially rectangular throat opening, an intermediate tubular body member joined to said front end member, and a rear end closure member joined to said body member to provide a substantially cubical structure open at the front, said front end member having an outwardly extending peripheral flange, each adjacent pair of said walls having a curved portion at their junction, each said curved portion being adjacent said flange and having a curved surface which is of increasing radius in a direction toward said rear closure member and is inclined outwardly in the opposite direction.

2. A fabricated sheet metal oven liner for a range comprising a front end member having a tubular portion, said tubular portion having top, bottom and side walls defining a substantially rectangular throat opening, an intermediate tubular body joined at one end to said front member and a rear end wall member joined to the other end of said body member to provide a substantially cubical structure having an opening at the front, said front end member having an outwardly extending peripheral flange, each adjacent pair of said top, bottom and side walls being disposed substantially in planes disposed at a right angle to each other, said adjacent walls having a first curved portion and a second curved portion at their junction, said first curved portion being adjacent said flange and being inclined inwardly in a direction toward said rear wall, at an angle to the axis of said second curved portion, said first curved portion lying wholly within the right angle formed by the intersection of said planes and serving as a corner brace to resist warpage or distortion of the liner.

3. The structure recited in claim 2 in which said first curved portion is a frusto-conical surface of increasing radius in a direction toward said rear wall.

4. A sheet metal oven liner comprising top, bottom, side and rear walls providing a substantially cubical casing having an opening at the front, a front peripheral flange disposed outwardly at an angle to said top, bottom and side walls, each adjacent pair of said last-mentioned walls having a curved portion at their junction, each said curved portion being adjacent said flange and having a surface of increasing radius in a direction toward said rear wall and being

inclined outwardly in the opposite direction, whereby said curved portion serves as a corner brace to resist warpage or distortion of the liner.

5. A sheet metal oven liner for a range comprising top, bottom, side and rear walls providing a substantially cubical casing open at the front, a front peripheral flange extending outwardly at an angle to said top, bottom and side walls, each adjacent pair of said last-mentioned walls having a first curved portion and a second curved portion at their junction, said first curved portion being adjacent said flange and being inclined outwardly with respect to said second curved portion, said first curved portion being substantially frusto-conical and increasing in radius in a direction toward said rear

wall and blending substantially tangentially with said adjacent walls to provide a smooth and rigid structure.

ALFONS BARNSTEINER.
